UNITED STATES PATENT OFFICE.

MARGARET EMMA SHOEMAKER, OF GRAND RAPIDS, MICHIGAN.

SHOE.

1,101,341.

Specification of Letters Patent. Patented June 23, 1914.

Application filed October 14, 1913. Serial No. 795,118.

To all whom it may concern:

Be it known that I, MARGARET E. SHOEMAKER, a citizen of the United States, residing at Grand Rapids, in the county of Kent 5 and State of Michigan, have invented new and useful Improvements in Shoes, of which the following is a specification.

Specifically stated, the object of the present invention is the provision of a shoe 10 upper wherein the closure flap is folded along its free edge, and slit at intervals for the reception of the flexible shanks of a row of buttons adapted to project from the marginal edge of the flap to add to the attractiveness and neatness of appearance of the 15 foot of the wearer, the parts being so arranged as to be secured together as a finished article by a single row of stitching.

The invention consists in the combination, 20 specific construction and arrangement of parts which will be hereinafter more fully described and particularly pointed out in the appended claims.

In the drawing forming a portion of this 25 specification and in which like numerals of reference indicate similar parts in the several views; Figure 1 is a perspective view of the shoe partly open showing the arrangement of buttons in accordance with my invention. Fig. 2 is a detail rear elevation of 30 the closure flap of the shoe. Fig. 3 is a sectional view taken on line 3-3 of Fig. 2. Fig. 4 is a detail perspective view of the flexible shank.

Referring to the drawing by numerals 1 35 designates the shoe upper, and 2 one of the flaps thereof to which the buttons 3 are secured in the ordinary well-known manner, the closure flap 4 being provided with the 40 usual button holes 5 for the reception of the said buttons.

My invention consists in the provision of a flat strip of non-metallic flexible material 45 preferably leather, of any suitable length to form the shank of the buttons 6. The strip is split longitudinally for a portion of its length from one end thereof to provide attaching tongues 7 and 8 which are bent in opposite directions and arranged within the 50 buttons 6 as shown in Fig. 2, the latter being molded on the said split end of the strip.

The closure flap 4 is folded upon itself beyond the button holes 5 thereof, and has 55 its marginal edge provided with a plurality of longitudinally extending slits 9 which are arranged at spaced intervals throughout its

length and in aline with the said button holes. The free ends of the strips are extended within the slits 9 and between the folds of the flap 4, the said slits being of suitable length to accommodate the said strips, which are secured therein in any suitable manner, preferably by stitching as indicated at 10 in the drawing. It will thus be seen that when the strips are so arranged within the slits 9 and between the folds of the upper 4, the said folds and strips may be readily and quickly secured together as a finished article by a single row of machine stitching. The strips when so arranged between the folds will cause the buttons 6 secured at the outer ends of the said strips to be arranged in upright position and in close proximity with the buttons 3 which admirably adds to the attractiveness and neatness 70 of the appearance of the foot of the wearer of the shoe.

It will thus be manifest that I have provided a shoe button with a flexible shank which is so constructed that any number of 80 said buttons may be readily and quickly secured to the shoe upper in the manner hereinabove set forth by a single row of machine stitching, and when so secured, said buttons will be disposed in upright position 85 directly opposite and in parallelism with the buttons 3 for the purpose hereinabove described.

It will be further obvious that the buttons 6 by reason of their arrangement provide 90 for a better purchase of the free edge of the flap 4 for the purpose of unbuttoning the shoe and which consequently facilitates such operation.

While I have shown and described the preferred form of my invention, it is to be understood that I am not to be limited to the precise construction and arrangement of parts herein shown and described, as various changes may be made within the scope of 100 the appended claims.

What I claim is:—

1. A shoe upper having button holes for the reception of the ordinary buttons, and a plurality of buttons having flexible shanks 105 secured to the marginal edge of the upper, in such manner that said buttons are arranged in line with and laterally of said button holes.

2. A shoe upper having button holes for 110 the reception of the ordinary buttons, and spaced slits in its marginal edge, and a plu-

rality of buttons disposed in line with and laterally of said button holes and having flexible portions secured within said slits.

3. A shoe upper folded upon itself and provided with spaced slits upon its line of fold, and a plurality of buttons having flat non-metallic flexible portions arranged within the slits and between the folds, and a

single row of stitching binding the fold and said flexible portions. 10

In testimony whereof I affix my signature in presence of two witnesses.

MARGARET EMMA SHOEMAKER.
